UNITED STATES PATENT OFFICE.

HOWARD PARKER, OF NASHUA, NEW HAMPSHIRE, ASSIGNOR TO IMPROVED PAPER MACHINERY COMPANY, OF CASTINE, MAINE, AND NASHUA, NEW HAMPSHIRE, A CORPORATION OF MAINE.

PAPER-MAKING ROLL.

SPECIFICATION forming part of Letters Patent No. 784,223, dated March 7, 1905.

Application filed June 1, 1903. Serial No. 159,526.

To all whom it may concern:

Be it known that I, HOWARD PARKER, a citizen of the United States of America, residing at Nashua, in the county of Hillsboro and State 5 of New Hampshire, have invented certain new and useful Improvements in Paper-Making Rolls, of which the following is a specification.

The object of my invention is to produce a device of the class specified having features 10 of novelty and advantage.

The drawing shows an embodiment of my invention in central vertical section.

a denotes a roll which may be of any desired construction having a foraminous surface and 15 preferably being provided with lengthwise compartments formed by suitable partitions. The roll is supported on the tubular sleeve a' , which extends beyond the roll at each end and is supported in suitable bearings, as shown at 20 a^2 . Within the roll this sleeve is provided with oppositely-arranged conical portions a^3 , which are perforated, as at a^4 . Suitable means are provided, as shown at a^5 , for rotating the roll. Plugs b are located in the extensions of the 25 tubular sleeve and are provided with conical ends b' , adapted in shape to the conical portions a^3 of the tubular sleeve a' . The conical ends of the plugs b are perforated part way around their periphery, as shown at b^2 , which 30 perforations are adapted to register with the perforations a^4 through the conical portions of the sleeve. These plugs are supported at their outer ends by the tubular sleeve, as shown at b^3 , and are held against rotation by any suitable means, as shown at b^4 . Suction is applied 35 to the interior of the roll a by connecting one of the plugs with a suction apparatus by means of the pipe c . The other plug is closed at its end, or it may be connected with another suction apparatus. The suction action generated 40 inside of the roll and between the ends of the plugs by suitable suction apparatus connected at the end of the pipe c tends to draw the two plugs toward one another and seat them in the 45 conical portions of the tubular sleeve, insuring

an air-tight fit, so that the different compartments in the roll as it rotates about the plugs will be subjected to the action of the suction as the perforations a^4 register with the perforations b^2 .

50

I claim as my invention—

1. A paper-making roll having a foraminous surface; a sleeve supporting said roll and having at each end non-cylindrical portions which are perforated; and plugs having perforated 55 ends adapted in shape to the non-cylindrical portions of the sleeve, said plugs being independent of one another, as and for the purposes specified.

2. A paper-making roll supported on a suitable sleeve having oppositely-arranged non-cylindrical portions, independent plugs having ends adapted in shape to the oppositely-arranged non-cylindrical portions of the sleeve, and registering perforations in the non-cylindrical parts, substantially as described.

3. A paper-making roll having a foraminous surface, a supporting-sleeve therefor, plugs independent of one another located within said sleeve, non-cylindrical coating bearing parts 70 on the sleeve and plugs having registering perforations, said plugs being connected with a vacuum-pump or its equivalent, as and for the purpose set forth.

4. A roll having a foraminous surface, a 75 tubular supporting-sleeve therefor, tubular plugs independent of one another located within said sleeve, and non-cylindrical coating bearing-surfaces on the sleeve and on the plugs, a closure for the outer end of one of the plugs 80 and a vacuum-pump or its equivalent attached to the outer end of the other plug, as and for the purposes set forth.

In testimony whereof I affix my signature in presence of two witnesses.

HOWARD PARKER.
